UNITED STATES PATENT OFFICE.

JOHN M. HOLLADAY, OF HOLLADAY, VIRGINIA.

AX-HEAD.

SPECIFICATION forming part of Letters Patent No. 447,685, dated March 3, 1891.

Application filed February 28, 1890. Serial No. 342,126. (No model.)

To all whom it may concern:

Be it known that I, JOHN M. HOLLADAY, a citizen of the United States, residing at Holladay, in the county of Spottsylvania and State of Virginia, have invented a new and useful Ax-Head, of which the following is a specification.

This invention relates to improvements in axes using removable, reversible, and interchangeable cutting-blades, and has for its main objects strength and simplicity of parts and cheapness of construction by adaptation for manufacture almost wholly by machinery.

With these general objects in view the invention consists in certain peculiar features of construction, hereinafter specified and particularly pointed out, as will be seen by reference to the accompanying drawings, in which—

20 Figure 1 is a side elevation of an ax-head provided with a removable, reversible, interchangeable cutting-blade constructed in accordance with my invention. Fig. 2 is a similar view of the head proper with blade removed. Fig. 3 is a section on the line $x-x$ of Fig. 1, and Fig. 4 is a perspective of removable blade. Fig. 5 is a section on line $5-5$ of Fig. 1.

25 This ax is made in two pieces, viz: the head proper 1, provided with the usual hole 9 for the handle and having two fingers 10 with an inverted-U-shaped recess 4 between them, and two downwardly-inclined shoulders 12, one on the outside edge of each finger. The fingers 10 have curved edges of V-shaped cross-section and the faces of the shoulders 12 are similarly shaped.

30 The cutting-blade 2, having a cutting-edge 8, is provided with one finger 5 to fit the recess 4 in the head and two U-shaped recesses 14 with concave edges to match the edges of the fingers 10 of the head. The blade is also provided with two downwardly-inclined shoulders 13 and the recess 14, and shoulders 13 all 45 have V-shaped slots in their edges to match the edges of those in the head, thus providing a perfect and rigid interlocking of the head and blade, which are additionally secured by two pins or rivets 7, and making an exceedingly strong connection between the parts, yet permitting easy separation and interchange, but avoiding all tendency either

to shackle or stick in the socket. The outer edges of the fingers 10 in the head and the notched edges of the end fingers of the blade 55 are provided with registering semicircular notches 3, and when the head and blade are brought together these notches form circular openings, in which rivets 7 are inserted. The ends of the latter may be sunk beneath the 60 faces of the ax-head, and then tamped to swell their bodies within said openings, as seen in Fig. 5, from which position they cannot become accidentally detached, although they can be driven out when desired, and where their 65 heads will not be struck by the material being chopped, thereby tending to dislodge them. The bodies of these rivets serve only to keep the tongues 10 from disengaging the recesses 14 vertically, all lateral disengagement being 70 prevented by the sharp edge on the head closely fitting the V-shaped groove in the blade. The downward incline of the faces 12 and 13 prevents the outer tongue from being sprung away from the ax-head, as might occur if the faces were horizontal or inclined upwardly, and the provision of the long tongues at each end of the blade member gives harder metal corners over which to pry, as in splitting wood. Although I have shown the rivets 7 as round, it will be understood that they 75 may be angular in cross-section; indeed, a square rivet would perhaps answer better, as all tendency to roll would be avoided. When worn at one end, the blade may be changed 80 end for end, and when dulled or nicked throughout it may be replaced by a new blade.

In some cases I may make the ax with only a single tongue, and will of course omit the 85 central tongue 5 of the blade; but I do not wish to be understood as in any way depreciating the value of the construction already shown and described.

I prefer to make the head 1 of cast steel, 90 although forged steel will answer equally well. The blade 2 is preferably of drop forged steel stamped into "blanks," shaped by dies into exact size, grooved along the upper edges by a rapidly-revolving cutter-wheel, and finally 100 ground or finished, although the mode of manufacture forms no part of the present invention. However, the commercial success of a tool of this character depends largely

upon the cheapness of its making, and I mention this to give a general idea of the simplicity of that process.

What I claim is—

- 5 1. The head 1, having on its lower edge the two fingers 10, interposed recess 4, and outer downwardly-inclined shoulders 12, in combination with the blade 2, having its upper edge formed with three fingers to fit said lower edge, and means, substantially as described, for removably connecting the said fingers with the blade, as set forth.
2. The head 1, having on its lower edge a

finger and downwardly-inclined shoulders 12 at each end of the head, in combination with 15 the blade 2, having its upper edge formed to fit said lower edge, registering notches 3 in said edges, and rivets 7, seated in said registering notches, substantially as described.

In testimony that I claim the foregoing as 20 my own I have hereto affixed my signature in presence of two witnesses.

JOHN M. HOLLADAY.
